UNITED STATES PATENT OFFICE

2,174,333

HEATING SYSTEM

Lewis Smith, Pelham, N. Y., assignor to Henry G. Schaefer, New York, N. Y.

Original application September 1, 1937, Serial No. 161,957. Divided and this application April 19, 1938, Serial No. 202,870

3 Claims. (Cl. 237—67)

This invention relates to heating systems for buildings and particularly, though not exclusively, to heating systems for apartment houses, hotels, hospitals and like buildings which have a considerable number of rooms and floors.

Savings in material, ready installation and low initial cost are prime considerations in the design of heating systems. It is the aim and object of the present invention to devise a heating system which has these desirable features to a remarkable extent.

This application is a division of my copending application Serial No. 161,957, filed September 1, 1937.

15 Before explaining in detail the present invention it is to be understood that the invention is not limited in its application to the details of construction and arrangement of parts illustrated in the accompanying drawings, since the 20 invention is capable of other embodiments and of being practiced or carried out in various ways. Also it is to be understood that the phraseology or terminology employed herein is for the purpose of description and not of limitation, and 25 it is not intended to limit the invention claimed herein beyond the requirements of the prior art.

In the drawing:

Fig. 1 is a fragmentary diagrammatic view of an installed heating system which embodies the present invention.

Fig. 2 is a front elevation, partly in section, of a type of radiator which may be used with particular advantage in the present system.

Referring to Fig. 1 of the drawing, the reference numeral 10 designates a building which may be an apartment house, a hotel, an office building, a hospital or a private home. In the present instance, the building is shown as having a basement 11 and three floors 12. However, the 40 building may have a different number of floors without impairing the adaptability of the present heating system to it. At 13 is shown a steam main which derives its steam from any suitable source such as a boiler (not shown) in the basement. Branching from the steam main 13 is a 45 conduit 14 which is carried to the topmost floor 12a through smaller rooms 15 of the building, such as kitchens, bathrooms, and the like, which may be sufficiently heated from the exposed ascending part or "up-feed riser" 14a of the conduit 14, thereby dispensing with radiators in the rooms 15. In the topmost room 15a, the conduit 14 is provided with a loop or bend 16 to provide for extra heating effect in compensation for heat lost through the roof 17. The conduit 14 is then

carried over to an adjacent larger room 18 on the top floor, such as a bed room, living room or the like, and is then carried down as a "down feed riser" 14b through the other rooms 18 on the various floors 12 and into the basement where it 5 is connected to the usual return main 19 through a conventional drip trap 19a. The down-feed riser 14b is connected in series with a radiator or radiators 20 in each room 18. These radiators may be of the inexpensive, yet durable construction disclosed in Fig. 2, and provide a metal cabinet or shell 21. The heating element 22 consists of a conduit 23 which has its heat-exchange surface augmented by a spiral fin 24, for instance. The down-feed riser 14b is connected with the 15 heating element 22 of each radiator 20 by any suitable means such as the elbows 25. No valve or trap is used in this type radiator. The radiator shell 21 is provided with an opening 26 in its bottom wall 27 through which air may enter, flow 20 past the heating element 22 and escape through a shutter 28 into the room. A knob 29 may be provided for manipulating the shutter between entirely closed position and wide open position to thereby regulate the escape of heated air from 25 inside the radiator shell and the admission of cooler air thereinto.

Any suitable control system may be used in the present heating system. Among others, the automatic control system which forms the subject 30 matter of my aforesaid copending application can be used with special advantage by maintaining a substantially constant low vacuum of perhaps 15 inches of mercury column in the entire piping system, including the return main 19, and by installing the radiator thermostat of my automatic control system in the radiator which is 35 nearest to the return main 19 in Fig. 1. In that way, fractional filling of the radiators is avoided because the radiator thermostat prevents the steam temperature at the end of the system from falling below a predetermined value and causes admission of steam to the system until even the last radiator thereof carries steam of sufficiently 40 high temperature to heat the room in which it is located without overheating the various rooms. Also, the condensate in the return main 19 may be removed therefrom by a vacuum pump, and a partial vacuum may be created in the up-feed 45 and down feed sections 14a and 14b of the riser 14 by throttling a main steam valve in the basement of the building. This main steam valve may be motor driven and automatically controlled in any suitable manner as by a thermostat 50 55

in the radiator nearest the return line 19, for instance.

Instead of one down-feed riser 14b branching off the top of the up-feed riser 14a, two or even 5 more down-feed risers may branch off the top of said up-feed riser and be then carried down through different rooms of the building. For instance, an additional down-feed riser (not shown) may be carried from the bend 16 over to 10 the topmost room 30 to the right of the room 15a and then down through the rooms underneath (not shown) and the radiators therein in exactly 15 the same fashion as the illustrated down-feed riser 14b in Fig. 1.

15 It is also within the present scheme to carry more than one up-feed riser through rooms which do not obtain sufficient heat from a single up-feed riser, and then branch over to adjacent rooms to the down-feed risers.

20 The present invention is not intended to be limited to the passage of the up-feed riser or risers through rooms in a building for the purpose of heating these rooms without radiators. In some cases, it may be preferred to have a 25 steam main at the top floor of the building and to connect a plurality of down-feed risers of the same arrangement as the one shown in Fig. 1 with said steam main. Steam from any suitable source may be conducted to the steam main at 30 the top floor in any convenient manner as by heat-insulated riser. The use of the disclosed down-feed riser in itself secures very valuable advantages without the benefit of the heating function of the up-feed riser, as will be hereinafter 35 explained.

The down-feed riser 14b which connects the radiators 20 in series may also be concealed and even heat-insulated, if desired.

40 The sectionalizing of the entire heating system of a building in so many up-feed risers and therefrom branching down-feed risers is a matter which varies greatly with different buildings and depends largely on the proportions of the large rooms, the proportion between the number of 45 small rooms and the number of large rooms, and the exposure of certain rooms.

In conclusion, the present heating system has the following advantages over the conventional 40 heating systems:

50 A minimum of piping because the return line is herein used as a down-feed steam line;
A minimum number of expensive fittings, valves and traps;
Well concealed heat-exchange elements of 55 the radiators;

Utilization of as much of the piping system as a heating surface as is consistent with the architecture of the building, and attaining economy of additional heating surface required, 60 space taken up by the system and heat-insulating material required;

65 Elimination of branch piping, either exposed or concealed, and hence elimination of stoppages and corrosion which shortens the life and improves the operation of piped systems, particularly when pipes and fittings of smaller sizes are used;

A minimum cubical contents of the entire system;

70 A minimum volume of the return system;
By supporting the down-feed riser at the place where it passes through the floor, or by supporting the radiator at the end where said down-feed riser enters, the length of the riser in each room and its radiator form an angle of piping

which is so constructed as to be sufficiently flexible 5 safely to take up the expansion and contraction strains in the pipes and thus eliminate expansion joints or bends.

These and other advantages are inherent in 5 the present heating system. The system of piping may be either for up or down feed, or for both. The radiators are made a part of the piping system by forming substantially horizontal (slightly inclined for condensate escape) 10 offsets of the steam-feeding riser, and they require neither valves nor traps. The radiators are preferably located under windows and made of such length that the vertical sections of the riser are located beyond the daylight openings 15 of said windows and may conveniently alternate on the several floors of the building on opposite sides of the windows as shown in Fig. 1.

While the heat available for emission by each radiator may be controlled by regulating the 20 pressure of the steam in the system in any well known manner to such an extent as to prevent fuel waste through excessive overheating, the heat output of any one radiator is further adjustable within limits defined by the manually 25 adjustable shutter or damper in the radiator shell, permitting of variation of the quantity of air admitted into said shell and, hence, the output of heated air therefrom.

It is to be understood that the present invention is not limited to the alternate disposition of the down-feed riser sections 14b on opposite sides of the radiators 20 as shown in Fig. 1. Thus, where the down-feed riser 14b connects radiators which are located beneath one of two 35 continuous corner windows in two rectangular walls of a room on each floor, and an exposed riser in the corner between these windows is undesirable, the riser sections 14b on the different floors are disposed in longitudinal alignment 40 with each other and to one side of said one window and remote from said corner. In that case, the lateral offset of the riser is immediately returned into realignment with the riser sections 14b, so that the riser extends through the 45 radiators in form of a loop, preferably of hairpin shape.

I claim:

1. The steam heating system for a building having rooms arranged one above another, which 50 comprises a riser passing downwardly from the top of the building heated by the system and having lateral offsets individually constituting a radiator in each room heated by the system, means for supplying steam to the riser at the 55 top thereof, the lateral offsets and intervening portions of the riser connected thereto constituting a complete, the sole possible and permanently uninterrupted path of flow for the steam, condensate and air in the same direction from 60 the steam supplying means to the return end of the system, and casings enclosing said lateral offsets, respectively, each casing having means for controlling the flow of air therethrough and consequently the amount of heat supplied to 65 each room.

2. The steam heating system for a building having series of overlying rooms, comprising an up-feed riser passing through the rooms of one series to the topmost room thereof and being 70 exposed in said rooms to heat the same, a down-feed riser connected with the upper end of the up-feed riser and having within the rooms of another series lateral offsets individually constituting a radiator, the up-feed riser and the 75

down-feed riser with its lateral offsets constituting a complete, the sole possible and permanently uninterrupted path of flow for the steam, condensate and air from the steam supply to the return end of the system whereby all of said radiators are simultaneously heated by the steam flowing through the radiators successively, and casings enclosing said lateral offsets, each casing having means for controlling the flow of air therethrough and consequently the amount of heat supplied to each room of said other series.

3. The heating system for a building having rooms arranged one above another, which comprises a riser passing downwardly from the top of the part of the building heated by the system and having lateral offsets individually consti-

tuting a radiator in each room heated by the system, means for supplying steam to the riser at the top thereof, the lateral offsets and intervening portions of said riser connected thereto constituting a complete, the sole possible and permanently uninterrupted path of flow for the steam, condensate and air in the same direction from the steam supplying means to the return end of the system, and casings enclosing said lateral offsets, respectively, each casing having means for controlling the flow of air therethrough and consequently the amount of heat supplied to each room, and said casings and their respective lateral offsets being separate units connectible with said intervening portions of the riser.

LEWIS SMITH.
